Julian H. Grubb Inventor

C. A. Snow & Co.

UNITED STATES PATENT OFFICE.

JULIAN HARMON GRUBB, OF HAGERSTOWN, MARYLAND.

NECKTIE-HOLDER.

SPECIFICATION forming part of Letters Patent No. 642,444, dated January 30, 1900.

Application filed May 3, 1899. Serial No. 715,409. (No model.)

To all whom it may concern:

Be it known that I, JULIAN HARMON GRUBB, a citizen of the United States, residing at Hagerstown, in the county of Washington and 5 State of Maryland, have invented a new and useful Necktie-Holder, of which the following is a specification.

This invention relates to necktie-holders, and has for its object to provide a collar-button with improved means adapted to engage the necktie and hold the same in place and prevent the tie from "riding" upward on the collar in front thereof.

To this end the present invention consists 15 in the combination and arrangement of parts, as will be hereinafter more fully described, shown in the accompanying drawings, and particularly pointed out in the appended claims.

20 In the drawings, Figure 1 is a sectional view of a shirt-band and collar, showing the collar-button equipped with the present invention and holding a necktie in place. Fig. 2 is an enlarged detail perspective view of 25 the collar-button. Fig. 3 is a longitudinal sectional view thereof. Fig. 4 is a sectional view showing the hinged head or plate in position for engagement of the collar-button with a collar. Fig. 5 is a detail perspective 30 view of the shank of the collar-button. Fig. 6 is a plan view of the bottom plate of the hinged head of the collar-button.

35 Corresponding parts are designated by like reference characters in all the figures of the drawings.

Referring to the accompanying drawings, 1 designates the base-plate of the button, preferably circular in form and provided with the shank 2, having its outer extremity reduced, 40 as at 3, bent or offset to one side of the shank, as shown, and provided with oppositely-extending pivot-pins 4. The free extremity of the reduced portion 3 is provided with a pointed prong or tine 5, which is located entirely at one side of the shank, extending beyond the end and inclined toward the plane thereof. The prong end of the shank is provided with a dished or concaved head 6, having a bottom plate 7, to which the edges of 45 the head are firmly clamped, so as to provide a hollow head. The bottom plate is provided with a longitudinal slot 8, having indenta-

tions or sockets 9 at opposite sides of the slot, near one end thereof, and arranged transversely of the slot. The purpose of this slot 55 is to facilitate the positioning of the head 6 upon the free end of the shank by receiving the pivot-pins 4 longitudinally through the said slot, after which the head is turned axially upon the reduced portion 3 of the shank, 60 so as to seat the pivot-pins 4 in the respective indentations 9 and transversely at opposite sides of said slot 8, the head also being provided with a longitudinal slot 10, alined with the slot in the bottom of the head, so as to 65 receive the prong or tine 5 and permit of the same projecting beyond the face of the head. Located within the head and snugly held by the walls thereof is a spring-plate 11, adapted to engage across the faces of the pivot-pins 4, 70 opposite the bottom plate 7. It will be understood that the pivot-pins 4 are preferably 75 square or angular in cross-section, so as to form a spring-hinge in connection with the spring-plate 11, whereby the head is held in either of its adjusted positions, and the upper face of the head 6 is provided with a longitudinal groove 12, extending from one end of the slot 10 outward toward the free end of the head and adapted to receive the prong 5 80 when the head is thrown into a position longitudinally of the shank for the purpose of engaging the collar-button with the button-hole of a shirt-band collar.

By reference to Fig. 1 it will be seen that 85 when the button has been applied to a collar-band 13 of a shirt and a collar 14 in the common and ordinary manner, the hinged head 6 being located transversely of the shank, the prong 5 will engage the rear side of a necktie 90 15 in a manner to hold said tie in its proper position and prevent the tie from riding upward upon the collar. Furthermore, it will be noted that the prong engages the necktie at the thickest portion and near the upper 95 edge thereof, whereby the tie is not twisted or strained and the shape thereof is preserved.

When the hinged head 6 is folded into a position longitudinally of the shank, as shown in Fig. 4, for the purpose of engaging the button with a buttonhole, it will be noted that the prong 5, being offset longitudinally to one side of the shank and the head being foldable upon the prong side thereof, permits of the 100

head being turned upon its hinged connection, so as to have its inner face or bottom plate alined with the shank, and the prong is received within the groove 12, whereby no 5 projections or obstructions are presented which might interfere with the proper and ready positioning of the collar-button.

The construction and arrangement of parts as hereinbefore described provide a simple 10 and exceedingly effective necktie - holder which is adapted to engage the necktie at the most advantageous part thereof, so as to preserve the shape of the necktie, and the prong is adapted to be conveniently housed by the 15 hinged head, so as to facilitate the engagement of the collar-button with a buttonhole.

Changes in the form, proportion, size, and the minor details of construction within the scope of the appended claims may be resorted 20 to without departing from the spirit or sacrificing any of the advantages of this invention.

What I claim is—

1. The combination of a collar-button having a base, a shank having its free end reduced and bent or offset to one side of the 25 shank, pivot-lugs projecting from opposite sides of the offset portion and the free end of the latter being formed into a prong or tine extending longitudinally beyond the end of 30 the shank, and a hollow head provided with alined longitudinal slots, and a longitudinal groove extending from the slot in the outer face of the head, and a spring-plate housed

within the head and provided with a slot alined with the slots in the head, the pivot- 35 pins of the shank being held between the bottom plate of the head and the spring-plate, whereby a hinged connection is provided for the head, and the prong or tine being adapted to project transversely through the outer slot 40 in the head and also adapted to be received within the groove thereof in the folded position of the head, substantially as and for the purpose described.

2. In a collar-button, the combination of a 45 base, a shank having a lateral offset portion at its outer end, a prong provided upon the outer end of the offset portion, and a head hinged to the offset portion, intermediate of the prong and the shank, and foldable upon 50 the prong side thereof, said head being provided with a slot receiving the prong, and a longitudinal groove in the outer face of the head, and extending longitudinally from one end of the slot thereof, and receiving the 55 prong flush with the outer face of the head, in the folded position thereof, substantially as and for the purpose set forth.

In testimony that I claim the foregoing as my own I have hereto affixed my signature in 60 the presence of two witnesses.

JULIAN HARMON GRUBB.
